UNITED STATES PATENT OFFICE.

EDWARD T. RYAN, OF NEW BEDFORD, MASSACHUSETTS.

HEAD-REST.

SPECIFICATION forming part of Letters Patent No. 379,987, dated March 27, 1888.

Application filed December 9, 1887. Serial No. 257,383. (No model.)

To all whom it may concern:

Be it known that I, EDWARD T. RYAN, a citizen of the United States, residing at New Bedford, in the county of Bristol and State of Massachusetts, have invented a new and useful Improvement in Head-Rests, of which the following is a specification.

My invention relates to that class of devices which are designed to be temporarily attached to a piece of furniture in order to serve as a support for the head.

The object of my invention is to provide a simple and portable device, more especially for barbers' use, which may be temporarily attached to a piece of furniture as a support for the head, and I attain this object by means of the device illustrated in the accompanying drawings, in which—

Figure 1 is a side view of my invention. Fig. 2 is a view showing the detail of a portion of Fig. 1, and Fig. 3 is a front view of the pad or cushion.

In Fig. 1, A represents a metallic bar, provided with the thumb-screw e, working through its lower end, said screw having the cap d loosely mounted on its point. The bar A is provided near its center with a square or oblong perforation for the reception of the squared shank of the angle-bar B. The shank of the angle-bar B is secured or clamped in the bar A by means of the thumb-nut e. The top of the bar A is perforated to receive the bolt o. The bolt o is provided with the loose collar m and the thumb-nut f, the position and arrangement of which are shown in Fig. 2.

The bolt o is perforated laterally near its head for the reception of the rod g. The end of the loose collar m which bears against the bar A is preferably corrugated or notched, as

is also that part of the bar A against which it bears, as shown at i. To the top of the rod g is secured the pad or cushion h, Fig. 3.

The operation of the device is as follows: The device is secured to a chair or other piece of furniture by some convenient portion of it being clamped between the jaw v of the adjustable angle-bar B and the end d of the thumb-screw e. The thumb-nut f is then loosened and the rod g adjusted to the desired height and angle with regard to the bar A, and is there secured by being clamped between the head r of the bolt o and the loose collar m by means of the thumb-nut f. By loosening the thumb-nuts f and e the rod g and angle-bar B may be removed from their position and the device carried in a very small compass.

Having thus described my invention, what I claim, and desire to secure by Letters Patent, is—

A head-rest consisting of the bar A, provided with a lateral opening through its body adapted to receive one arm of the angle-bar B, and provided with the thumb-screw e, for clamping said arm, one end of said bar A being provided with the thumb-screw c, working laterally through it, and the other end having a lateral opening for the reception of the bolt o, provided with the thumb-screw f, loose collar m, and a lateral perforation near its head, in which the rod g, provided with cushion h, is adapted to be adjusted in any desired position and clamped by means of the thumb-nut f, all as shown and described.

EDWARD T. RYAN.
